CLIP ATTACHMENT FOR TELEPHONES

Bernard B. Friedman, Chicago, Ill.

Application March 13, 1959, Serial No. 54,983

Term of patent 7 years

(Cl. D26—14)

Fig. 1 is a perspective view of a clip attachment for telephones embodying my new design;

Fig. 2 is a front elevation of the clip attachment shown in Fig. 1;

Fig. 3 is a side elevation of the clip attachment;

Fig. 4 is a rear elevation of the clip attachment; and

Fig. 5 is a top plan view of the clip attachment.

The broken line portions in Fig. 1 are for illustrative purposes.

I claim:

The ornamental design for a clip attachment for telephones, substantially as shown and described.
